(57) **CLAIM**

The ornamental design for a splicing toy, as shown and described.

DESCRIPTION

FIG. 1 is a perspective view of a splicing toy showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the splicing toy where the splicing toy is in a configuration of use; and,

FIG. 10 is a perspective view of one of the 24 identical components of the splicing toy, shown in isolation.

The broken lines in the drawings depict portions of the splicing toy that form no part of the claimed design.

1 Claim, 10 Drawing Sheets
